DESIGN FOR A BATHROOM SHELF BRACKET

Jacques F. Levy, New York, N. Y.

Application January 2, 1936, Serial No. 60,392

Term of patent 3½ years

To all whom it may concern:

Be it known that I, Jacques F. Levy, a citizen of the United States and resident of Manhattan, city, county, and State of New York, have invented a new, original, and ornamental Design for a Bath Room Shelf Bracket, of which the following is a specification:

Reference is to be had to the accompanying drawing which forms a part of the specification

and in which Fig. 1 is a top view of the bath room shelf bracket; Fig. 2 is a bottom view; Fig. 3 is a side view and Fig. 4 is a front view, all of these figures showing my new design.

I claim:

The ornamental design for a bath room shelf bracket.

JACQUES F. LEVY.
